HARRY K. HEDGES, OF LOS ANGELES, CALIFORNIA.

PUMP.

1,262,664.

Specification of Letters Patent. Patented Apr. 16, 1918.

Application filed May 2, 1914. Serial No. 835,919.

To all whom it may concern:

Be it known that I, HARRY K. HEDGES, a citizen of the United States, residing at Los Angeles, in the county of Los Angeles 5 and State of California, have invented new and useful Improvements in Pumps, of which the following is a specification.

This invention relates to pumps, and more particularly to that class of pumps designated as displacement pumps, in which compressed air is utilized for raising liquids, by the application of the compressed air directly on the surface of successive charges of the liquid, such charges being thereby 10 driven out of suitable displacement chambers.

The invention has for its object to provide a pump of the general character stated, which will be relatively simple and inexpensive in construction, positive, highly efficient and economical in operation, and whereby those losses which accompany, in present practice, the utilization of compressed air or other suitable elastic medium 15 in the direct application thereof to the liquid to be raised, are eliminated. This object is attained by such provision, combination or interrelation of elements and features, that the elastic medium employed for raising the liquid, or a portion of such medium, is employed to control the operation of the pump by operating a suitable controlling member or members for controlling the admission and exhaust of the elastic medium 20 to the displacement chambers, the controlling member or members being positioned adjacent thereto, such member or members in turn being subject to the control of a distributing timer which may be placed exteriorly of the well, mine, shaft, or the like in which such pump is installed. The controlling member or members being placed at or near the point of work and being controlled through the elastic medium itself, the pump is especially well adapted for 25 use in deep wells where the great distance between the displacement chambers and the means of controlling the operation thereof would necessitate, in pumps organized in accordance with standard practice, the use of long and heavy connecting means, or would result, in cases where the medium itself is controlled at such distances from the point of work, without the intermediation of the controlling member or members, in great loss of energy due to the wasting of the

stored energy of the elastic medium filling the enormous clearance space in long pipes, the clearance space of the pipes being in fact a wasteful extension of the clearance space of the displacement chamber. 60

The invention consists in the provision, construction, formation, combination and relative arrangement of parts, members and features, and the general organization and mode of application and operation thereof, all as hereinafter described, shown in the drawing and finally pointed out in claims. 65

In the drawing:

Figure 1 is a fragmentary vertical transverse sectional view of a portion of a deep well, such as a deep oil well, showing the improved pump installed therein; 70

Fig. 2 is a view similar to Fig. 1, showing the reverse side of the pump, the displacement chambers being shown in section; 75

Fig. 3 is a vertical transverse sectional view of one of the controlling members, taken on the line x^3-x^3 , Fig. 1, and looking in the direction of the appended arrows; 80

Fig. 4 is a view similar to Fig. 3, being a vertical transverse sectional view of the other controlling member, taken on the line x^4-x^4 , Fig. 1, and looking in the direction of the appended arrows; 85

Fig. 5 is a horizontal transverse sectional view taken on the line x^5-x^5 Fig. 2, and looking in the direction of the appended arrows;

Fig. 6 is a view similar to Fig. 5 taken on the line x^6-x^6 , Fig. 2, and looking in the direction of the appended arrows; and 90

Fig. 7 is a view similar to Figs. 5 and 6, taken on the line x^7-x^7 , Fig. 2, and looking in the direction of the appended arrows. 95

Corresponding parts in all the figures are designated by the same reference characters.

Referring with particularity to the drawing, A designates generally the hole of a deep well within which liquid to be pumped is shown as at a. The improved pump is shown as comprising in the main a plurality of displacement chambers B and C and controlling members D and E for the respective chambers B and C. These controlling members being subject to control by a master controller or distributing timer F shown at the orifice of the well, such control by the master controller F over the controlling members B and E being had through the medium of the elastic working fluid. The displacement chambers B and C 100

105

110

22

are preferably formed in a cylindrical shell 8, the chamber B being provided with a discharge duct 9 and an inlet check valve 10, a discharge check valve 11 being provided in 5 an enlargement 9^a at the upper end of the duct 9, such valve co-acting with a suitable seat 12 in the end wall 9^b of the duct 9. A seat 13 for the inlet valve 10 is formed in the bottom wall 14 of the chamber B. The 10 chamber C is likewise provided with an inlet check valve 15, a discharge check valve 16, located in an enlargement 17^a provided in a discharge duct 17, the discharge check valve 16 being provided with a seat 18 in 15 the end wall 17^b of the duct 17, a seat for the inlet valve 15 being provided in the bottom wall 19 of the chamber C.

In the embodiment of the invention shown in the drawing, the construction of the displacement chambers, which will be readily understood by reference to Figs. 1, 2, 3 and 4, is particularly well adapted for use in deep wells of small diameter, compartments being formed, one on each side of a vertical transverse central partition 20 dividing the cylindrical shell 8 into the chambers B and C, the discharge ducts 9 and 17 being formed by semi-circular walls 21 and 22 respectively, such walls 21 and 22 being made 25 integral with the partition 20, one on each side thereof, and each extending to within a short distance of the bottom of its respective chamber B or C, the partition 20 extending the full length of the chambers B and C 30 merging into the top wall 8^a and the bottom wall 8^b thereof. A discharge valve chamber 23 is provided at the top of the cylindrical shell 8, to provide space for the play of the valves, a discharge pipe 24 for the liquid 35 being threaded as at 24^a into the top wall 25 of the valve chamber 23.

The controlling members D and E each comprise a cylinder 26 and a piston valve 27 mounted therein and adapted to be reciprocated through the medium of the working fluid, the interval between reciprocations of the pistons 27 being determined by the speed at which the timer F is driven, as will hereinafter be described. The cylinders 50 26 each are provided with an inlet port 28 and a discharge port 29, other ports 30 and 31 being provided in the cylinder walls at a point substantially diametrically opposed to the ports 28 and 29 respectively, these 55 latter ports communicating through short pipes 32 and 33 with the displacement chambers, the pipe 32 leading from the ports 30 and 31 of the controlling member D to the upper portion b of the displacement chamber B, and the pipe 33 leading from the ports 30 and 31 of the controlling member E to the upper portion c of the displacement chamber C. The piston valves 27 are 60 cut away or provided with circumferential 65 reduced portions forming passages 27^a and

27^b. When the piston valves are at one end of their stroke the passages 27^a are in registration with and establish communication between inlet ports 28 and the ports 30 and working fluid is allowed to pass through 70 that controller member which is so set, to the respective displacement chamber connected to it through the short pipe 32 or 33. When the piston valves are at the other end of their strokes the portions 27^c of the 75 pistons cover the inlet ports 28 and the ports 30 terminating the admission of working fluid to the chambers therethrough, but permitting the escape or exhaust of the previously admitted portion of such fluid from 80 the displacement chambers, when it has performed its function in driving out the charge of liquid to be raised, such escape or exhaust being through the ports 31, the passage 27^b and the exhaust ports 29 and to and 85 through the exhaust pipe 34 which is bifurcated at its lower end, the furcation 34^a connecting with the exhaust port 29 of the cylinder 26 of the member D and the furcation 34^b to the other exhaust port 29 provided in the cylinder 26 of the member E. It will be understood that, though the controlling members D and E are described as operating in exactly the same manner, they do not operate to admit and exhaust 90 working fluid to the chambers simultaneously, but alternate in their action, for during such time as the piston valve of the member D is admitting air to the displacement chamber B the piston of the member E is positioned so that the passage 27^b registers with the port 31 and the exhaust port 29 provided in the cylinder 26 of the member B permitting exhaust of the working fluid 95 in the chamber C. The piston valves 27 being subject to control by the timer they are allowed to remain in the positions just described for a predetermined time and then 100 their positions are reversed, that is, the piston valve 27 of the member D will be moved into such position that the portion 27^c of that piston valve will terminate the admission of working fluid to the chamber B by covering the port 30 and the inlet port 28, the portion 105 of the piston valve 27^d uncovering the port 31 and exhaust port 30, the passage 26 then being in registration with the port 31 and the exhaust port 30, the working fluid previously admitted to the chamber B will be allowed to escape or exhaust, and the piston valve 27 of the member E will now be in 110 such position that its passage 27^e will be in registration with the port 30 and the inlet port 28 of the member E, admitting the working fluid to the displacement chamber C to expel the liquid therein, the port 31 and the exhaust port 30 of the member E being closed by the portion 27^d of its piston valve. A supply pipe 35 for the working 115 fluid leads from the distributing timer F to 120

125

130

the cylinder head 26^a of the member D where it connects with the interior of the cylinder above the portion 27^c of the piston valve. A branch pipe 35^a springing from the pipe 35 leads into the inlet port 28 provided in the cylinder wall of the member E, an extension 35^b of the branch pipe leading to the lower cylinder head 26^b of the member E and communicating with the interior of the cylinder below the portion 27^d of the respective piston 27. A similar supply pipe 36 for the working fluid leads from the distributing timer F to the cylinder head 26^a of the member E and communicates with the interior of the respective cylinder 26 above the portion 27^c of the piston valve 27. A branch pipe 36^a springs from the pipe 36 and leads into the inlet port 28 of the member D, an extension 36^b of such branch pipe leading to the lower cylinder head 26^b and communicating with the interior of the cylinder 26 of the member D below the portion 27^d of the respective piston valve 27.

The distributing timer F comprises a distributing cylinder 37 provided with ports 38 and 39, a supply pipe 40 for supplying the elastic medium or working fluid being tapped into the cylinder between the ports 38 and 39, and a piston rod 41 provided at its ends with pistons 42 and 43 which are cut away as at 42^a and 43^a respectively to form circumferential grooves or channels. The chamber 44 formed by the pistons 42 and 43 and the walls of the cylinder 37 is always in direct communication with the supply of elastic medium as delivered by the pipe 40, connection being made between the chamber 44 and the channel 42^a by a duct 42^b a similar duct 43^b being provided in the piston 43 through which the channel 43^a communicates with the supply of elastic medium in the chamber 44. The piston is provided with a connecting rod 45 through which it is reciprocated by any suitable device as for instance the eccentric shown at 46. The supply pipe 35 leading to the controllers is connected to the distributing cylinder 37 at the port 38 thereof, the supply pipe 36 being connected at the port 39 of the distributing cylinder 37.

The operation, method of use and advantages of the pump herein described and shown in the drawing will be readily understood, particularly in and by the following statement:

A supply of compressed air or other elastic medium from any suitable source is connected with the chamber 44 of the distributor by the pipe 40, and by reciprocation of the pistons 42 and 43, alternately admitted to the supply pipes 35 and 36, the arrangement of the pistons being such that when the pipe 35 is being supplied with air through the duct 42^b, the channel 42^a and the port 38, the pipe 36 is free to

exhaust, the port 39 being then uncovered by the piston 43. When, however, the pistons are moved to the other end of their stroke through the action of the eccentric 45, the connections are reversed; the pipe 36 now receiving compressed air from the chamber 44 through the duct 33^b, the channel 43^a and the port 39, the port 38 being now uncovered the compressed air in the pipe 35 may exhaust therethrough and through the open end of the distributing cylinder to the normal atmosphere. This alternate admission and exhaust of compressed air to the pipes 35 and 36 actuates the piston valves causing reversal of their positions with each admission and exhaust into the supply pipes 35 and 36. When compressed air is admitted to one of the pipes and therethrough to one of the cylinders 26, at the top portion thereof, the piston in that cylinder is driven down and the piston valve 27 therein is in position to permit exhaust of the previously admitted charge of compressed air in the respective displacement chamber which it controls, while at the same time one of the timer pistons uncovers a port 38 or 39 and the other supply pipe is in position to exhaust through its respective port in the distributing cylinder, and the pressure on top of the portion 27^c of the piston 27 in the other cylinder 26 is released; air from the branch pipe extension leading to the lower cylinder head 26^b forces the piston valve up or in position to admit compressed air to its respective displacement chamber through the branch pipe supplying it, to inlet port 28, passage 27^a, port 30 and the short pipe connecting the port 30 with its respective displacement chamber. When one of the piston valves is in position to admit compressed air to its displacement chamber, the compressed air so admitted forces the charge of liquid in that chamber out through its respective discharge check valve, and into or through the discharge pipe 24, which leads to the desired level to which the liquid is to be raised. While one chamber is thus discharging its liquid, a charge of liquid is entering the other chamber through its intake valve and driving out the air therein, its controlling member piston valve being in position to permit exhaust.

The alternate reciprocation of the piston valves of the controlling members in opposite directions of travel to opposite positions due to the lifting by the compressed air of one of the pistons, while air from the same pipe depresses the other piston perfectly controlling the admission and exhaust of the compressed air into the displacement chambers as regulated by the distributing timer F, so that by the same stroke the distributing timer F permits admission of elastic medium to one displace-

ment chamber and consequently causes expulsion of the liquid therein, it permits the escape through the exhaust pipe 34 of such elastic medium as has just finished its work of expulsion in the other displacement chamber, and the displacement chambers being submerged, liquid automatically enters and fills the chamber which will be ready for discharge when the distributing timer F 10 again acts to reverse the position of the piston valves 26 which reversal will take place when the charge of liquid, in the chamber discharging, has been expelled. The interval between reversals or alternate discharges 15 may be accurately adjusted by simply driving the timer at the proper speed to meet the requirements of any particular installation. When the timer is so adjusted the liquid will issue from the discharge end of 20 the pump in a smooth even stream free from pulsations.

Having thus described my invention, I claim and desire to secure by Letters Patent:

25 1. A pump of the character disclosed, comprising a plurality of displacement chambers adapted for submersion and provided each with a liquid intake valve and a liquid discharge valve, and means for supplying an elastic medium under pressure to said chambers, said means comprising a supply pipe for each of said chambers, a distributing timer having ports therein controlling the admission and exhaust of the elastic 30 medium to and from said supply pipes, a controlling cylinder for each of said chambers, and a controlling valve in each of said controlling cylinders, there being ports in said cylinders through which said elastic 35 medium is passed, subject to control by said controlling valves, said controlling valves being actuated by said elastic medium in its travel *en masse* to and from said displacement chambers, whereby the actuation of said controlling pistons is governed by 40 said distributing timer.

2. A pump of the character disclosed, comprising a plurality of displacement chambers adapted for submersion and provided 45 each with a liquid intake valve and a liquid

discharge valve and means for supplying an elastic medium under pressure to said chambers, said means comprising a supply pipe for each of said chambers, a distributing timer controlling admission of elastic 55 medium to said pipes, and independent controlling cylinders, one for each of said displacement chambers; said controlling cylinders being located adjacent said displacement chambers and each provided with elastic medium admission ports and elastic medium discharge ports, and each having a piston therein to control said ports; one of said supply pipes being connected with each of said cylinders to cause the actuation 60 of the respective piston valve and being connected with another of said cylinders at the elastic medium inlet port thereof and connected with such cylinder near one end to admit elastic medium to actuate the piston therein whereby alternate admission of elastic working fluid by said distributing timer to said supply pipes, causes the reciprocation of the piston valves as the working fluid is cut off or supplied to the displacement chambers. 70

3. In apparatus of the character disclosed, a tubular body provided at one end with a plurality of inlet valves and at the other end with a plurality of discharge valves, 80 and having a vertical partition ranging from end to end thereof to divide such tubular body into a plurality of displacement chambers adapted for submersion; there being ducts formed on each side of said partition and each terminating at one end of one of the discharge valves and terminating at the other end at a point slightly above one of the inlet valves and whereby liquid may be conveyed under the pressure of an 85 elastic working fluid past said discharge valves. 90

In testimony whereof, I have signed my name to this specification in the presence of two subscribing witnesses.

HARRY K. HEDGES.
